UNITED STATES PATENT OFFICE.

PETER J. IHRIG, OF SPRINGFIELD, OHIO, ASSIGNOR OF ONE-HALF TO JUSTUS K. IHRIG, OF SPRINGFIELD, OHIO.

PORTABLE TREE-HOLDER.

1,401,259.

Specification of Letters Patent. Patented Dec. 27, 1921.

Application filed May 16, 1921. Serial No. 470,151.

To all whom it may concern:

Be it known that I, PETER J. IHRIG, a citizen of the United States, residing at Springfield, in the county of Clark and State of Ohio, have invented certain new and useful Improvements in Portable Tree-Holders, of which the following is a specification, reference being had therein to the accompanying drawing.

10 This invention relates to improvements in portable tree holders, designed particularly for use at Christmas time for the support of Christmas trees set up within the household at such time.

15 The invention consists, essentially, of a frame and a clamp with mechanism to adjust the clamp to and from the frame so that the tree may be embraced, irrespective of its diameter, between the frame and the 20 clamp, and thus be held securely in an upright position.

The invention consists further of numerous features of detail as will hereinafter appear.

25 In the accompanying drawings;

Figure 1 is a side elevation of my improved tree holder;

Fig. 2 is a plan view thereof;

Fig. 3 is a detail side elevation of a portion of the clamp and one of the adjusting pinions; and

Fig. 4 is a detail view of the stud shaft and detent, which latter is used to engage a rack wheel in holding the clamp in adjusted positions.

The numeral 1 designates two uprights whose lower ends are adapted to be inserted in or to be secured to a suitable base 2, sufficiently extended in size and heavy enough to

40 maintain the uprights in a standing position, with or without the use of securing means, such as screws 3. Braces 4 aid in securing the fixed relation of the uprights 1 to the base 2. The two uprights are connected together by cross beams 5 and 6. A

45 shaft 7 is mounted in bearings in the uprights and equipped with two pinions 8, a ratchet wheel 9 and a crank 10. A detent 11 is carried on a stud shaft 12 which projects from one of the uprights. The stud shaft

50 has a spline 13 through a part of its length and the detent has a hole 14 adapted to fit the stud shaft and a seat 15 which permits the detent to be slipped past the spline, 55 when it may drop down and by its weight

engage the teeth in the ratchet 9. To sustain the detent out of contact with the ratchet wheel it is simply necessary to lift it and shift it on the shaft until the spline 13 enters the seat 15, which will hold the detent 60 in an elevated position. A mere touch by the finger will cause the detent to drop back into the teeth of the ratchet.

The uprights are further provided with guide blocks or surfaces 16 and 17 between 65 which, on the inner side of the uprights, is placed the clamp composed of side bars 18 each having a toothed rack 19 and interconnected by a cross beam 20, at one end.

The pinions 8 engage with these toothed 70 racks so that when they are revolved through the shaft 7 and crank 10 the clamp will be brought against, or adjusted away from, the trunk of the tree indicated at 21, which occupies a position between the side bars 18 75 of the clamp, the cross beam 20 and the cross members 5 and 6 of the main frame. Therefore, when the clamp is adjusted tightly against the tree the latter will be held firmly in the adjusted or upright position. The 80 bottom of the tree will rest on the base 2 or other support by which the frame is maintained in a vertical position.

The construction of my tree-holder is simple, all the major parts being straight. It 85 is easily operated and readily applied to a tree, which may either be dropped down between the cross bar 20 of the clamp and the members 5 and 6 of the frame, or may be brought within the clamp by running the 90 racks clear off of the pinions and placing the clamp about the tree.

The portable quality or character of my holder adds to its utility since it may be placed anywhere about the household that it 95 is desired to have the Christmas tree.

Having thus fully described my invention, what I claim as new and desire to secure by Letters Patent, is:—

1. In a tree holder, the combination with 100 a frame comprising a base, perpendicular uprights extending therefrom, a shaft longitudinally mounted in the uprights, and pinions near each end of the shaft, of a clamp having side bars mounted to slide in 105 the uprights, racks on the side bars adapted to engage the pinions on the shaft, and means to secure the clamp in adjusted positions to maintain its grip upon a tree.

2. In a tree holder, the combination with 110

a frame, comprising a base, perpendicular uprights extending therefrom, a shaft longitudinally mounted in the uprights, and pinions near each end of the shaft, of a clamp having side bars and a cross-beam, said bars adapted to slide in the uprights, racks on said side bars adapted to mesh with said pinions and a detent and ratchet mechanism to secure the clamp in adjusted positions.

3. In a tree holder, the combination with a frame comprising a base, perpendicular uprights extending therefrom, cross-members, a shaft longitudinally mounted in the uprights, and pinions near each end of the shaft, of a clamp comprising two side bars, a cross-beam connecting said side bars at one end, a toothed rack-bar on each side bar, a ratchet on the end of the horizontal shaft,

and a detent carried by the frame to engage 20 with the ratchet.

4. In a tree holder, the combination with a frame comprising a base, two perpendicular uprights extending therefrom, cross-members and guiding blocks, a horizontal 25 crank shaft mounted in the uprights, a pinion near each end of the shaft, and a ratchet wheel on one end thereof, of a clamp comprising two side bars fitting between the guide blocks, a rack on each of said bars 30 adapted to mesh with the pinions respectively, a cross-bar connecting said side bars, and a detent mounted upon the frame to engage the ratchet wheel to secure the clamp in adjusted positions to maintain its grip 35 upon a tree.

In testimony whereof, I affix my signature.
PETER J. IHRIG.
